US00D956801S

(12) **United States Design Patent** (10) Patent No.: **US D956,801 S**
Downie et al. (45) Date of Patent: **** Jul. 5, 2022**

(54) **DISPLAY SCREEN WITH A GRAPHICAL USER INTERFACE FOR A COOLER PACK**

(71) Applicant: **MEDELA HOLDING AG**, Baar (CH)

(72) Inventors: **Kathy Downie**, McHenry, IL (US);
Carl Huval, McHenry, IL (US);
Claudia Kowanda, Oberägeri (CH)

(73) Assignee: **MEDELA HOLDING AG**, Baar (CH)

(**) Term: **15 Years**

(21) Appl. No.: **29/772,780**

(22) Filed: **Mar. 4, 2021**

Related U.S. Application Data

(62) Division of application No. 29/719,749, filed on Jan. 7, 2020, now Pat. No. Des. 916,117, which is a division of application No. 29/638,278, filed on Feb. 26, 2018, now Pat. No. Des. 875,477.
